UNITED STATES PATENT OFFICE.

VICTOR CÁCERES, OF NEW YORK, N. Y.

STREET-CLEANING MACHINE.

1,245,675.

Specification of Letters Patent.

Patented Nov. 6, 1917.

Application filed September 13, 1916. Serial No. 119,818.

To all whom it may concern:

Be it known that I, VICTOR CÁCERES, a citizen of Colombia, and a resident of the city of New York, borough of Manhattan, in the county and State of New York, have invented a new and Improved Street-Cleaning Machine, of which the following is a full, clear, and exact description.

Among the principal objects which the present invention has in view are: to provide a machine for removing snow or other deposit from streets of municipalities; to break hardened formation preparatory to removing the same; to provide a special mechanism for elevating and loading series of independent vehicles; and to simplify the mechanism required for the performance of the above-stated objects.

Drawings.

Figure 1 is a side elevation of a carrier and loader constructed and arranged in accordance with the present invention;

Fig. 2 is a top plan view of the same; Fig. 3 is an enlarged detail view showing in vertical section a fragment of the loader;

Fig. 4 is a detail view on an enlarged scale showing a fragment of the power shovels used in conjunction with the present invention, the view being taken as on the line 4—4 in Fig. 3;

Fig. 5 is a detail view on an enlarged scale showing a modified form of the invention when employed as a trailer and as having breaker bars for shattering masses of ice or other deposit;

Fig. 6 is a cross section, the section being taken as on the line 6—6 in Fig. 5.

Description.

As seen in the drawings, a plurality of scoop-like shovels 11 are mounted on pivot shafts 12, which are supported in bearings 13 formed at the ends of cross braces 14. The braces 14 reinforce the side disks 15 producing a drum-like construction. Each shovel has striking brackets 16 which are held against the braces 14 by springs 17.

The shovels 11 are relatively short. A series of said brackets extend across the full width of the drum formed by the disks 15. This arrangement accommodates any uneven surfaces of roads, and avoids the total failure of all the shovels due to some irresistible obstruction in the path of one or more of said shovels. The springs 17 are

provided to permit the shovels when striking such an obstruction, to be retracted by and to pass over the same. In operation and as shown in Fig. 5 of the drawings, the shovels assume a retracted or dragging angle and are thereby loaded.

When the loaded shovel is lifted by the rotation of the disks 15 out of engagement with the roadbed or covering thereof, the springs 17 return the same until the brackets 16 strike the braces 14. This lift is sufficiently graduated as to prevent the discharging of the contents of the shovel. When, however, these shovels are lifted against the under side of the boot 18, they are forced backward to an excessive degree to be suddenly released to permit the springs 17 to rotate the said shovels and to strike the brackets 16 violently upon the braces, thereby dislodging or tossing the load carried by the said shovels upwardly and forwardly into the boot 18.

The drum formed by the disks 15 and braces 14 is supported by a trailer frame 19, which is carried on wheels 20. The wheels 20 operate as tractors for driving the drum, said wheels being provided with a driving pulley 21, which is connected with a driven pulley 22 on the shaft 23 of the said drum by means of a twisted belt 24. By the arrangement of the belt 24 with reference to the pulleys 21 and 22, the drum carrying the shovels 11, is rotated reversely to the wheels 20, or in the direction indicated by the arrow *a* in Fig. 5.

The boot 18 is suitably supported on the trailer frame 19 to cooperate with a belt conveyer 25 and buckets 26 with which the same is provided.

A sprocket 21^a is connected with the sprocket 27 and thereby drives the conveyer 25 in the direction indicated by the arrow *b* in Fig. 5.

The buckets 26 when passing over the boot 18 are loaded with the material deposited therein by the shovels 11, and on reaching the top of the conveyer to pass over the drum 28, the said buckets deliver the load on the apron 29. The fender 30 assists in guiding the load to the apron 29. As shown best in Fig. 1 of the drawings, the apron 29 is held in horizontal suspension by a brace arm 31 which supports a drum 32, at the outer end whereof is mounted a gear wheel 33. When the arm 31 is properly adjusted to the active service po-

95

110

sition, the gear wheel 33 is meshed with the gear wheel 34 on the cart or carrier having a body 35. The object served by the employment of the gear wheels 33 and 34, 5 is to drive a skeleton load-distributing belt 36. The belt 36 is driven as indicated by the arrow *d* in Fig. 1 of the drawings, and is furnished with a series of spreader bars 37, which operate to scrape the top of the 10 load deposited in the body 35 toward the forward end thereof whenever the top of the load extends into the path of the forwardly-moving bars 37.

The movement described which is imparted to the apron 29 results from the employment of a short belt 49. In the modified form shown in Fig. 5 of the drawings, this belt is replaced by a longer belt 50 which is connected with the bottom drum 20 of the conveyer 25 rather than with the top drum.

The framework of the conveyer 25 may be of any desired pattern. That shown in the drawings is one where supporting bars 51 25 are employed for supporting the upper drum 28.

As shown in Fig. 1 of the drawings, the trailer is preferably self-propelled, being provided for this purpose with a motor 38, 30 steering wheel 39, controlling levers 40, and driver's seat 41. Any suitable form of tractor mechanism may be employed. The object of the independent tractor feature is to permit the independent movement of the 35 machine to and from the field of operation.

In the modified form of the invention shown in Fig. 5 of the drawings, the machine is employed as a trailer, being operatively connected by a link 42 or other suit-

able means to the cart or carrier. The beater 40 bars 43 shown in Figs. 5 and 6 of the drawings, are employed to shatter or break any lumps or masses which may have formed in the roadway or street. The bars are each rotatively mounted on a pivot bar 44, the 45 upper ends of said bars being in juxtaposed relation to a tappet shaft 45. Rigidly mounted on the tappet shaft 45 are tappet disks 46, each of which is provided with a lug or pin 47 to strike the upper end of its 50 companion bar 43, and to force the same forward, thereby lowering the lower end thereof as best shown in Fig. 5.

Connected with each bar 43 is a pull spring 48. The springs 48 operate to violently 55 retract the bars 43 to their normal position when released by the pins 47, and thereby shatter the lumps or other massed formation of snow or other debris on the roadbed with which they come in contact. 60

Claim.

A machine as characterized comprising a body having carrying wheels; a rotary drum operatively connected with said 65 wheels; a plurality of shovels mounted on said drum; a conveyer boot carried by said body in receiving relation to said shovels; and means for emptying said shovels after the same are raised above the receiving end 70 of said boot, said means embodying a plurality of yielding connections operable for normally maintaining the radial position of said shovels to said drum, and abutments 75 for receiving the impact on said shovels when thrown against said boot by said yielding connections.

VICTOR CÁCERES.
